(57) **CLAIM**

The ornamental design for a control device for an automated warehousing system with a user interface, as shown and described.

DESCRIPTION

FIG. 1 is a front perspective view of our design for a control device for an automated warehousing system with a user interface;

FIG. 2 is a front view thereof;

FIG. 3 is a rear view thereof;

FIG. 4 is a top plan view thereof;

FIG. 5 is a bottom plan view thereof;

FIG. 6 is a right side elevational view thereof, the left side elevational view being a mirror image of FIG. 6; and,

FIG. 7 is an enlarged front view of the display panel portion. The broken lines are shown for illustrative purposes only and form no part of the claimed design.
